UNITED STATES PATENT OFFICE

ADOLPH C. JAEGER, OF PORT CHESTER, NEW YORK

DESIGN FOR A TEXTILE FABRIC OR SIMILAR ARTICLE

Application filed December 10, 1932. Serial No. 46,423. Term of patent 7 years.

To all whom it may concern:

Be it known that I, ADOLPH C. JAEGER, a citizen of the United States, residing at Port Chester, county of Westchester, State of New York, have invented a new, original, and ornamental Design for a Textile Fabric or Similar Article, of which the following is a specification, reference being had to the accompanying drawing, which forms a part thereof, and in which I have shown a unit of the design in full lines, and have indicated how the design may be repeated by the broken lines.

In the figure, the shading indicates contrasting surface appearance, e. g., contrasting surface texture.

I claim:

The ornamental design for a textile fabric or similar article substantially as shown and described.

Signed at New York, N. Y., this 8th day of December, 1932.

ADOLPH C. JAEGER.
